EARTH MOVING DEVICE

Willis H. Yount, Oakland, Calif., assignor to
American Tractor Equipment Corporation, a
corporation of California

Application September 16, 1936, Serial No. 101,113

5 Claims. (Cl. 37—126)

This invention relates to a new and improved scraper structure and, more particularly, to an improvement upon that large earth carrier and scraper structure shown in the copending application of John F. Knapp, Serial No. 58,552 of January 10, 1936, and Robert B. Price, Serial No. 80,726, of May 20, 1936.

The present invention is concerned with an improved mechanism for controlling the scraper blade elevation and for operating the bowl closure means. While the machines of the aforementioned applications were successful, the present structure is much more rugged, and, at the same time, simpler in construction.

It is an object of the present invention to simplify further the operating mechanism for the bowl closure means, particularly to the end that the bowl closure means can be operated by only a single cable in a large capacity carrier-scraper.

It is an object of the present invention to simplify the elevating mechanism on a cable operated scraper structure, to provide a simple and yet rugged structure.

The invention includes other objects and features of advantage, some of which, together with the foregoing, will appear hereinafter, wherein the present preferred scraper structure of my invention is disclosed. In the drawings accompanying and forming a part of this specification, Figure 1 is a side elevation partly in section of a scraper structure embodying my invention.

Figure 2 is a plan view, partly in section.

Figure 3 is a section illustrating the detail of construction at the hinge forming point.

35 *The frame*

The scraper of the present invention includes a strong steel frame 11 made up of a plurality of members, usually secured together by spot welding. This frame includes side member 12, end members 13, and a forward member 14. This member joins the side members 12 and extends forwardly to provide a support for bearing 16 and forwardly extending uprights 17.

45 A front truck 18, including an axle 19 upon which are positioned wheels 21, is provided to permit steering of the scraper. A draw bar 22 extends forwardly to be attached to a suitable hitch on such a vehicle as a tractor used to propel the scraper. The axle 19 carries a ball member 23 which is received in a socket 24 at the bottom of a post 26. This post extends upwardly and is connected to member 14 by a pair of links 27 engaged with the post by shaft 28 intermediate the ends of the post. A shaft 29 inserted in

bearing 16 connects the other link ends to member 14. Another pair of links 30 are connected at the top of the post by shaft 31 and to the upright 17 by shaft 32. The links 27 and 30 provide a parallel linkage connection between the 5 scraper frame and the front truck post 26.

Wheels 36 are provided at the rear of the frame in pairs, each pair being mounted upon an axle 37, each axle being carried in the supporting members 38.

10

The bowl

Secured to the frame members 12 are suitable side plates 41. Between these side plates are extended a bottom plate 42 and an arcuate plate 43. At their forward ends these plates are joined together and thus provide a lip 44 to which is attached a suitable cutting blade 46, bolts 47 being usually utilized for this purpose so that the cutting blade can be readily changed or replaced.

Upon advancing the scraper over the ground 20 the cutting blade 46 will cut off and pick up earth, this earth being deposited upon the arcuate plate 43 to be retained therein.

Since the point at which it is desired to dump 25 a load from the scraper may be a considerable distance from the point at which the load is picked up, since transportation of the load may result in accidental discharge of a part thereof, I provide means for retaining the earth in the bowl. This means is shown as comprising two 30 arms 45 carried upon stub shafts 48 which are in turn carried by brackets 49 on side frame members 12. These arms extend forwardly and provide a hoe-like door structure with transverse plates 50 and 51 which are welded between the arms 45. It is to be noted that plate 51 engages the cutting blade and thus insures a tight closure 35 for the bowl.

To provide for removal of earth carried upon 40 the bowl I support another pair of arms 61 from stub shafts 48 and extend between these arms an end gate in the form of a plate 62. It is to be noted that the center of curvature of the arcuate plate 43 is the center of the stub shafts 48 and that plate 62 will sweep over and wipe off earth upon the plate 43 so that the bowl can be readily 45 emptied.

The blade elevating mechanism

Means are provided for raising and lowering 50 the frame 11 so that the position of the cutting blade 46, relative to the earth, can be adjusted. In the form disclosed this means comprises a pulley structure 71 supported upon a pin 72 car- 55

ried by rearwardly extending arm 73 on the post 26. A second pulley structure indicated at 74 is supported upon the end of member 14. A cable 78 is secured to the frame of pulley 71 and is 5 extended about the several pulleys to secure a multiplication in the power applied on cable 78. This cable extends over a guide pulley 77 carried on one side of post 26 and about a guide pulley 79 positioned by support 81 for universal movement. The pulley extends to a suitable hoist mechanism, usually a hoist at the rear of a tractor.

The closure and end gate operating mechanism

15 In accordance with this invention, a very simple and yet practical form of cable operating mechanism is provided for the door and the end gate structure. An offset arm 82 extends rearwardly from the upright 17 which is carried by 20 the forward part of the frame portion 14. The arm 82 carries a multi-groove pulley 83 carrying a cable 85 which extends forwardly over guide pulley 86 on extension 17 and through a guide pulley 87 on the other side of post 26 to another 25 guide pulley 88 on extension 81 to a suitable cable operating mechanism on the tractor. The cable 85 is extended between the multi-groove pulley 83 and a like pulley 89, the end of the cable being secured to the frame adjacent pulley 30 88. The pulley 89 is supported in a link structure 90 which in turn is carried by a shaft 81 on the end closure or door. Plates 50 and 51 are so connected that a recess is provided between them. The link structure permits raising of the door 35 to the maximum height, enabling the pulley 89 to swing out clear of the door as it is raised.

It is to be noted that arms 81 each include an outwardly extending extension 101 thereon and that from each of arms 45 an ear 102 projects 40 over each of the extensions 101 so that arms 45 can only be moved a limited distance before ears 102 engage the extension 101. Thereafter, further rotational movement of arms 45 about the stub shafts will result in a rocking of the end 45 gate 82 over the base of the bowl until finally the end gate is in the dot line position shown in Figure 1, and the closure means, including arms 45, have been moved to the extreme or uppermost position in which they appear in dotted 50 lines in Figure 1.

To provide for the return of the end gate I extend a spring 141 in the frame 13 transversely on the scraper bowl so as to secure a goodly length thereof. A piston 143 engages an end of this 55 spring and to this piston is attached a cable 144. This cable is extended to the end gate about suitable guide pulleys 147 so that when the end gate is moved forward it is only against the bias of the spring so that the spring always urges the end 60 gate to return to that position in which it appears in Figure 1.

Operation

While it is believed that the operation of the 65 structure is relatively clear from the foregoing description, it will be again pointed out upon a pulling of cable 78, a raising and lowering of the cutting blade relative to the edge can be secured the cable passing over suitable pulleys provided 70 between the frame of the scraper and the post 26, to raise and lower the two pairs of links relative to each other.

As to operation of the bowl, once the bowl is 75 filled it is raised relative to the earth, the door or closure means provided by arms 45 and plates

50 and 51 being lowered into position. Normally the scraper is operated in about that position in which it appears in Fig. 1 with the scraper blade in contact with the earth, the door being raised to the position shown in the dash lines. When 5 the closure means is to be lowered, the operator simply releases the tension upon cable 85, the weight of the closure means causing it to drop into the full line position and plates 51 will be in engagement with the cutting blade 46 while 10 arms 45 are above the dirt in the bowl. If cable 78 be pulled to bring link pairs 27 and 30 together, the blade will be raised above the earth and the load carried.

When it is desired to dump the load the operator 15 operates the hoist pulling on cable 85. This results initially in a lifting of the door or closure means. During the initial movement of the closure means the end gate will not be moved. However, continued pulling on cable 85 results in 20 continued rotation of the arms 45 and rotation of closure 82. This gradual raising of the closure means brings it into that position in which it appears in Figure 1, well elevated above the bowl and the closure 82 into a position wherein 25 all dirt has been swept off the bowl.

During the movement of the end gate the spring has of course been placed under tension so that, upon the operator releasing the cable 85, the end gate 82 is returned while the weight of 30 the closure means causes it to rotate about the stub shafts and return to the full line position in which it appears in Fig. 1. The operator usually stops the fall of the door when it is in an intermediate position and spaced from the bowl so 35 that earth can be scraped up and gathered in the bowl.

It is to be pointed out that the load on the dirt moving gate is substantially uniform. Thus when the gate is first moved the load is made up 40 of dirt on the bowl and little if any power is demanded by the spring. As the dirt is forced out over the cutting edge the dirt load decreases but more power is demanded by the spring. This results in a uniform loading on the cables. The 45 door position enables the operator to judge the operation of cleaning the bowl accurately.

I claim:

1. A scraper comprising a bowl, means for discharging dirt therefrom including a gate supported above said bowl and movable thereover to discharge dirt thereon, closure means for said bowl hinged above said bowl and movable from a bowl closing position to a raised position above the bowl, said closure means including arms adjacent each side of said bowl, means extending from said gate and engaging said arms only after opening movement of said closure means, and means for moving said gate including a pulley carried by said gate, a pulley supported above 50 said gate and a cable extended between said pulleys.

2. In a scraper, a frame providing an opening, wheels at the rear end thereof, means supporting the front end of said frame, a bowl carried by 65 said frame and extending from in front of said wheels toward said frame front end, an end gate for ejecting dirt from said bowl, a door for closing said bowl supported for hinged travel from a bowl closing position to a raised position, means 70 supporting said gate over said bowl, a pulley on said door, a second pulley carried adjacent said frame front end, a cable extended between said pulleys for lifting said door, and means connecting said gate to said door to move said gate con- 75

currently with said door at least during a portion of the travel of said door.

3. In a scraper, a frame having a front end, a bowl mounted on said frame to the rear of said front end, a door for closing said bowl including a bowl engaging portion and a forwardly and upwardly extending portion supplementing said bowl as a dirt carrier, a first pulley on said door adjacent said forward end, a second pulley carried on said front end above said bowl, a cable extended between said pulleys, and a link hinged on said door adjacent said bowl engaging portion and interposed between said door and the first pulley to swing said pulley free of said door upon lifting of said door.

4. In a scraper, a frame having a front end, a bowl mounted on said frame to the rear of said front end, a door for closing said bowl and movable from a bowl closing to a bowl opening position, a first pulley carried by said door, a second pulley carried on said front end, a cable extending between said pulleys to lift said door, a gate positioned above said bowl, and means inter-

engaging said gate and said door to move said gate with said door only after initial movement of said door away from said bowl.

5. In a scraper, a dirt carrying bowl having a cutting blade to cut and deliver dirt to said bowl, a door supplementing said bowl and including a blade engaging portion and an extending portion providing a supplemental bowl portion when said door is in blade engaging position, a gate movable over said bowl to eject dirt therefrom, means connecting said gate to said door for concurrent movement with said door at least during a portion of the travel of said door, a link hinged on said door adjacent the blade engaging portion of the door, said link extending along said door in a recessed portion of the door, a pulley on the link, a second pulley, means supporting said second pulley elevated above said door in blade engaging position, and a flexible element trained over said pulleys and movable to lift said door until said link swings out of said recessed portion.

WILLIS H. YOUNT.
